UNITED STATES PATENT OFFICE.

WILLIAM AUGUST SMITH, OF DENVER, COLORADO, ASSIGNOR OF ONE-HALF TO
WILLIAM W. HASSELL, OF COLORADO SPRINGS, COLORADO.

ROCK-DRILL.

1,191,842.

Specification of Letters Patent. Patented July 18, 1916.

Application filed July 20, 1912. Serial No. 710,635.

To all whom it may concern:

Be it known that I, WILLIAM AUGUST SMITH, a citizen of the United States, residing at Denver, in the county of Denver and State of Colorado, have invented new and useful Improvements in Rock-Drills, of which the following is a specification.

This invention relates to certain new and useful improvements in rock drills, and the object thereof is to provide an improved and novel construction of rock drill.

In the drawings: Figure 1 is a side elevation of the invention, partly in section; Fig. 2 is an enlarged fragmentary sectional view; 15 and Fig. 3 is a section on the line 3—3 of Fig. 1.

Cylinder 1 has a large bore 2 and a small bore 3, a piston 4 operating in the bore 3 and being connected by a pitman 5 to a 20 crank 6 that is mounted in a crank case 7. A hammer 8 operates in the large bore 2 and has an extension 9 that is received in the front end of the small bore 3. On the backward stroke of the piston 4 a partial vacuum 25 is created in the space 10 between the adjacent ends of the hammer extension 9 and the piston 4 which effects rearward movement of the hammer until the hammer 8 closes a port 11 that communicates by means of a 30 passage 12 with the interior of crank case 7. The closing of port 11 results in compression of the air between hammer 8 and the inner wall 13 formed by the large bore 2 of the cylinder effecting stoppage of the hammer.

35 At the same time the piston 4 in its rearward travel uncovers and opens an air inlet valve 14, permitting air to enter the small bore 3. When the piston 4 moves forwardly it compresses the air in space 10 driving the hammer forward, and as the hammer starts on 40 its forward travel it opens a relief valve 15 that communicates with the large bore 2, causing a breaking of any partial vacuum that may exist in bore 2. When the extension 45 of hammer 8 moves past an outlet valve 16 that communicates with bore 3 it permits escape therethrough of the air that has been compressed in space 10 causing the hammer to be freed of further pressure. The hammer engages a striking plug 50 17, and should for any reason the hammer not strike plug 17, the compressed air in cushion chamber 20 stops the blow.

55 Relief valve 19 does not open on the forward stroke of the hammer but opens when

the hammer starts back to relieve any portion of the vacuum in chamber 20 caused by the rearward movement of the hammer, the same as valve 15 acts on rear end. The valve 19 serves to increase the inlet area of chamber 20 and when 18 is closed at both ends, affords the sole means of communication between 18 and 20. Upon the forward movement of the piston it creates a partial vacuum in passage 12 which draws air from the large bore 2 through port 11 and also from chambers 18 and 20 thus assisting in the forward propulsion of the hammer by removing the resistance that the air in said chambers would naturally offer if present. 60 When piston 4 starts forward it acts to cause air with a rush to be drawn from duct 12 before valve 21 can open for a period sufficient to relieve the vacuum. The inlet area of valve 21 is very slight, as compared 65 with the piston area, consequently but little air can pass through same during a certain period. Since the piston 4 causes a sudden pulsation on its forward movement an air valve 21 on crank case 7 is opened for an 70 instant until hammer 8 travels forward to relieve the vacuum as above described. The valve 21 acts to overcome all outlet leaks and to maintain atmospheric pressure in the crank case 7, passage 12 and chambers 18 75 and 20.

75 The front end of cylinder 1 has a head 22 which is formed with a water passage 23 that receives water from a tapped plug 24 or any other suitable connection which connects with any suitable source of supply by a pipe or hose, not shown. Passage 23 leads to a spacer ring 25 which is perforated to allow the water to enter a port 26 that is formed in a rotating sleeve 27. The spacer 80 ring 25 is sealed by packing 28 at its ends. Sleeve 27 which is made in two sections has its inner section formed with an annular flange 29 that rotates in a pocket formed between head 22 and a ring 30 secured in the 85 outer end portion of cylinder 1. An adjusting nut 31 threaded into head 22 enables the packing to be adjusted as desired. A water pipe 32 is inserted in sleeve 27 and registers with the port 26 therein and is carried by a 90 taper or cone nut 33 which is threaded into engagement with the sleeve 27. Pipe 32 is secured to the rotating drill bit 34 by means of a series of ears 35 formed on drill 34 and bent to engage with said pipe on its opposite 95 100 105 110 115

sides to allow of relative free sliding movement of the parts.

Since the point of discharge of the water from the water pipe 32 is at all times directed at the drill 34 during the reciprocation of the latter, it will be apparent that the hole being drilled will be continually flooded and consequently washed out, carrying off the products that result from the 10 drilling operation.

What is claimed is:

1. The combination with a cylinder having a large bore and a small bore and a crank case forming an extension of the 15 small bore, a piston in the small bore, an air inlet valve communicating with the small bore, an inwardly opening air valve on the crank case, a hammer in the large bore having an extension that operates in 20 the small bore, an inwardly opening relief valve in the large bore at the juncture between the bores, an outwardly opening valve between the relief valve and the air inlet 25 valve of the large bore, said cylinder having a passage which communicates with the crank case and the front end of the hammer, a pair of chambers at the front end of the hammer and a relief valve between said chambers.
- 30 2. In combination with a cylinder having a crank case connected thereto, a piston in the cylinder, a hammer actuated by the piston, a relief valve in the hammer bore, said cylinder having a passage which connects the hammer bore and crank case, and an inwardly opening valve in the crank case.

Copies of this patent may be obtained for five cents each, by addressing the "Commissioner of Patents, Washington, D. C."

3. In combination with a cylinder having a crank case connected thereto, a piston in the cylinder, a hammer actuated by the piston, means whereby the hammer is cushioned upon its return stroke, means to break the vacuum in the space between the piston and hammer when the piston reaches the 40 limit of its backward stroke, and means whereby a partial vacuum is formed at the 45 front and rear ends of the hammer upon movement of the piston on its working stroke.

4. In combination with a cylinder having a crank case connected thereto, a piston 50 in the cylinder, a hammer actuated by the piston, means whereby the hammer is cushioned upon its return stroke, means to break the vacuum in the space between the piston and hammer when the piston reaches the 55 limit of its backward stroke, means whereby a partial vacuum is formed at the front and rear ends of the hammer upon movement of the piston on its working stroke, and means to allow the air compressed 60 between the hammer and piston to escape when the hammer has completed its working stroke.

In testimony whereof I have hereunto set my hand in presence of two subscribing 65 witnesses.

WILLIAM AUGUST SMITH.
